SEWING MACHINE CARRYING CASE

Emile P. Tarlé, Paris, France, assignor to The Singer
Manufacturing Company, Elizabeth, N. J., a corpora-
tion of New Jersey

Application September 30, 1954, Serial No. 32,496

Term of patent 14 years

(Cl. D87—5)

Fig. 1

Fig. 2

Fig. 3

Fig. 4

Fig. 1 is a perspective view of a sewing machine carrying case showing my new design,

Fig. 2 is a top plan view of the sewing machine carrying case shown in Fig. 1,

Fig. 3 is a front elevational view of the same, and

Fig. 4 is an end elevational view of either end of the carrying case.

The rear elevational view of the carrying case is the same as that shown in Fig. 3.

The characteristic and essential parts of my design of a sewing machine carrying case, which has walls slanting toward the top, reside in (1) that the sewing machine carrying case is entirely symmetrical in appearance, and (2) that all of the external surfaces of the sewing machine carrying case present a smooth and undivided appearance.

I claim:

The ornamental design for a sewing machine carrying case, substantially as shown and described.
